ATTORNEY.

UNITED STATES PATENT OFFICE.

CLAUDE A. P. TURNER, OF MINNEAPOLIS, MINNESOTA.

DRAWBRIDGE.

1,106,259.

Specification of Letters Patent.

Patented Aug. 4, 1914.

Application filed December 27, 1913. Serial No. 808,939.

To all whom it may concern:

Be it known that I, CLAUDE A. P. TURNER, of Minneapolis, in the county of Hennepin, and in the State of Minnesota, have invented a certain new and useful Improvement 5 in Drawbridges, and do hereby declare that the following is a full, clear, and exact description thereof

My invention relates to draw bridges of 10 the type shown in United States Patent No. 503,273, issued August 13, 1893, to P. A. Warner and myself, and the object of my invention is to improve the mechanism of that patent for raising the toggle joint for 15 lifting the ends of the arms of the draw span preliminary to opening, or swinging the bridge. In that patent the apex of the toggle is connected by a transverse pin to the lower end of a vertically movable 20 screw by the revolution of which the toggle joint is raised or lowered and there are certain objections to the construction which is the object more particularly of my present invention to obviate.

My invention, therefore, relates particularly to the mechanism for imparting the desired vertical movement to the toggle joint.

In the accompanying drawings—Figure 30 1 is a top plan view in the nature of a diagram showing a draw bridge of the type of that of the patent above mentioned; Fig. 2 is a side elevation thereof the full lines showing the bridge in its closed position and the dotted lines showing the position of the parts when the toggle joint has been raised to lift the bridge arms from their bearings on the abutments; Fig. 3 is a detail view in vertical section of the toggle 35 joint lifting mechanism; Fig. 4 is an end elevation thereof with parts in section; Fig. 40 5 is a top plan view thereof.

In its general construction, as may be seen by reference to Figs. 1 and 2, the drawbridge shown corresponds to that of said bridge Patent No. 503,273, that is to say, the bridge 45 is mounted upon a central turn table 10 which supports the two oppositely extending arms 11, said arms having at their inner 50 ends struts 12 which at their point of connection with the top chords of the arms at their upper ends are connected to the outer ends of the toggles 13, the inner ends of the toggles being brought together and lapped 55 past each other and connected by a transverse pin 14, the holes in the toggle eyes be-

ing horizontally elongated to allow for the necessary play upon the pin due to the vertical movement of the toggle joint.

The toggle pin 14 rests in a semi-circular 60 bearing in the top of a saddle 15, which at each side of the pin has a horizontal extension 16 with an internally threaded hole through which passes a vertical screw 17, the two screws being, respectively, right and 65 left handed and suitable bearing being provided in the frame work 18. Upon each of the screws 17 is keyed, or otherwise secured, a gear 19 and between the two gears 19 and meshing with both of them is a pinion 20 70 upon a vertical operating shaft 21 by the revolution of which, either by hand or by power, the screws are simultaneously revolved in opposite directions and the saddle thereby caused to move vertically and the 75 toggle joint thereby raised when the direction of the revolution of the screws is such as to move the saddle and the toggle pin 14 thereon upward. It will be seen that by the employment of the two screws there is no 80 torsional or twisting effect whatever upon the pin 14 which results from the single screw and nut arrangement of the construction of the patent before mentioned, and hence, tendency of the latter to bind in the guides 85 22 between which the pin at its opposite ends project, is avoided, so that the toggle pin 14 moves upward smoothly and freely without any binding tendency from sidewise or lateral movement; and it will be seen that 90 in other respects my present toggle joint lifting mechanism is desirable in that it is simple, its members being of the simplest kind, and it is easily operated and powerful.

Having thus described my invention what 95 I claim is—

1. As an improvement in end lifts of center bearing draw bridges, the combination of a toggle, a toggle pin at the joint, a pair of rotary screws at opposite sides of the 100 toggle pin, connections between the screws and the toggle pin, and means for revolving said screws.

2. As an improvement in end lifts of center bearing draw bridges, the combination 105 of a toggle, a toggle pin at the joint, a pair of rotary screws at opposite sides of the toggle pin, connections between the screws and the toggle pin, and means for revolving said screws, the screws having, respectively, 110 right and left thread.

3. As an improvement in end lifts of

center bearing draw bridges, the combination of a toggle, a saddle having a bearing for the toggle pin, threaded openings through the saddle at opposite sides of the pin, a screw passing through each opening, and means for revolving the screws.

4. As an improvement in end lifts of center bearing draw bridges, the combination of a toggle, a saddle having a bearing for the toggle pin, threaded openings through the saddle at opposite sides of the pin, a

screw passing through each opening, said screws having right and left thread, gears on the respective screws, and a driving pinion between the two gears meshing with ¹⁵ both of them.

In testimony that I claim the foregoing I have hereunto set my hand.

CLAUDE A. P. TURNER.
